UNITED STATES PATENT OFFICE.

RICHARD HUDNUT, OF NEW YORK, N. Y.

DESIGN FOR A BOTTLE-STOPPER.

SPECIFICATION forming part of Design No. 36,186, dated December 30, 1902.

Application filed November 6, 1902. Serial No. 130,358. Term of patent 7 years.

To all whom it may concern:

Be it known that I, RICHARD HUDNUT, a citizen of the United States, residing at Manhattan borough, New York city, in the county of New York and State of New York, have invented and produced a new, original, and ornamental Design for a Bottle-Stopper, of which the following is a specification.

My invention relates to a new, original, and ornamental design for bottle-stoppers, and is illustrated in the accompanying drawings.

In the drawings, Figure 1 is a perspective view of the stopper, and Fig. 2 is a plan view thereof.

The leading feature of my design consists of a crown surmounting a column, the top of the column provided with a plurality of bands of different diameters and the lower portion of the column provided with a series of bands of different diameters, the lower series of bands terminating in a convex flange of greater diameter, and the flange sitting on a cylindrical column of greater diameter than the first-mentioned column.

In the drawings the reference character *a* denotes the crown-shaped portion of the stopper, the latter at its bottom sitting upon the band *c*, the band *c* mounted upon the band *c'*,

and the band *c'* mounted upon the band *c''*, the band *c''* being of smaller diameter than the band *c'*. The band *c''* is mounted upon the column *b*, which is cylindrical in contour, and the column *b* rests upon the band *c'''*, which is of larger diameter than the column *b*. The band *c'''* is mounted upon the band *c''''*, the latter being of larger diameter than the band *c'''*. The band *c''''* is mounted upon the band *c'''''*, the latter being of larger diameter than the band *c''''*. The band *c'''''* is mounted upon the convex flange *d*, which is of greater diameter than the band *c'''''*. The convex flange *d* rests upon the column *e*, which is cylindrical in contour and of greater diameter than the column *b*.

What I claim as new, and desire to secure by Letters Patent, is—

The ornamental design for a bottle-stopper substantially as herein shown and described.

In testimony whereof I have hereunto set my hand in the presence of two subscribing witnesses.

RICHARD HUDNUT.
